UNITED STATES PATENT OFFICE.

CHARLES P. EISENHAUER, OF DAYTON, OHIO, ASSIGNOR TO THE DUBO COMPANY, OF DAYTON, OHIO, A CORPORATION OF OHIO.

WATER-SOFTENING APPARATUS.

Original application filed July 6, 1925, Serial No. 41,580. Divided and this application filed December 28, 1925. Serial No. 77,949. Renewed June 11, 1928.

My invention relates to valves and is a division of my application Serial No. 41,580, filed July 6, 1925.

It is the object of my invention to provide a valve particularly attached to water softening apparatus having means for being moved yieldingly in one direction, hydrostatically in the other direction and locked in a given position, together with means for effecting the interlocking at a pre-determined time.

Referring to the drawings:

Figure 1 is a side elevation of a complete automatic softening apparatus with the softening tank partially in section and with the salt tank in section;

Figure 2 is a section through a typical hydraulic valve;

Figure 3 is a view partially in section of a softening line valve;

Figure 4 is a view partially in section of the by-pass valve;

Figure 5 is an elevation partially in section showing the locking mechanism of the refill valve;

Figure 6 is a view partially in section of the salt valve.

Referring to the drawings in detail, 1 designates the incoming hard water line which passes through an apparatus actuated by the hard water such as a water meter, generally designated 2.

The line from the meter is designated 48. It meets a vertical pipe at right angles designated 49 which leads to the bottom of the softener tank 50 which communicates with, at the point marked 51 beneath the grating 52, the screen 53 which is carried by the grating. This screen and grating are retained in position by the bolts 54. The liquid passes upwardly through the softening material 55, through the screen 56 mounted on the grating 57. The bolts 58 retain these pieces in position. The liquid passes out at a point above the screen on top of the tank at 59, through the pipe 60 to the fitting 61 which contains an injector. This fitting is connected on one side to the pipe 60 and on another side to the pipe 62 from the pipe 48. On a third side it is connected to the brine line 63 and on the fourth side it is connected to the outgoing service line 64. This service line is connected to the incoming hard water line by-pass pipe 65 which leads into the fitting 66 in which is a portion

of the valve member of a by-pass valve 41. The pipe 67 leads to service, for either hard or soft water depending upon the state of the system. The brine line contains a valve 43 which is the refill valve and a valve 45 which is the brine valve. It enters the brine tank 46 at 68 and goes downwardly to the bottom of the brine tank where it terminates in a bell 69 which is a slight distance above the bottom of the tank and which is buried beneath the layer of gravel designated 70.

A valve 38 controls the passage of the hard water from the meter to the bottom of the softener tank 50 and the valve 36 controls the passage of the hard water from the main line to the top of the tank 50. A general control valve is designated at 22, a pipe 35 extending from this valve to the valve 36, which in turn communicates by a pipe 37 with the hard water inlet valve 38. The valve 38 is connected by a pipe 34^b to a drain valve 34 in the drain line 34^a. A pipe 33 connects the control valve 22 with the drain line to permit the escape of any accumulated liquid in the chamber of the control valve 22. A pipe 40 leads from the control valve 22 to the by-pass valve 41, a pipe 42 connecting the by-pass valve 41 to the refill valve 43, which in turn communicates with the brine valve 45 through a pipe 44. A pipe 47 leading from the brine valve 45 to the brine tank 46 serves to carry away any waste from the train of valves 41, 43 and 45.

The float 71 in the brine tank which is supported on the float arm 72 is pivoted at 82 on the refill valve 43. This float arm 72 is connected to a bell crank 81 pivoted at 82 on a bracket 83 on the housing 84 of the refill valve 43. The lower end of this bell crank has pivotally connected to it at 85 a plunger 86 which is guided at one end in a bracket 87 carried by the housing of the valve 43 and at the other end is guided in an aperture 88 in the side wall of the housing. A helical spring 89 surrounds the plunger 86. It is located between the bracket 87 and the cotter pin 90 carried by the plunger 86. The head of this plunger 86 is adapted to be thrust above the piston 91 which is carried on the piston rod 92. This piston rod 92 is connected to the diaphragm 93.

There is provided at 80 on the end of the bell crank 81 a vertical link 79 which has an elongated slot 78 at its upper end. Working

in this slot is a transverse pin 77 carried in the jaws 77^a of the lever 115. The lever 115 is pivoted at 73 upon the vertical member 74 which acts as its support. The bottom of the pivotal support is pivoted at 75 upon the casing 76 which is a cover of the brine valve 45.

The construction of the lower part of the refill valve can be seen in Figure 2. A valve stem 94 is threaded at 95 in the piston and piston rod 91 and 92 respectively. This valve stem extends downwardly into the brine line where it seats against a partition 96 arranged in that line, such partition having an orifice 97 within a valve seat 98 against which the valve member 99 seats. This valve member is carried on the lower end of the valve stem 94. Beneath the valve seat is provided an aperture 100 in the pipe which is closed by a screw plug 101 for draining and cleaning purposes. Below the piston 91 is located a helical spring 102 one end of which abuts the piston, the other end of which abuts a top 103 of a screw plug 104 which fits into the base 25 of the casing 43 of the valve. This spring is located within a chamber 105. Threaded into the interior of the screw plug 104 is an upwardly projecting dome like member 106 which acts as the upper retaining member 30 for an interiorly located spring 107 which is mounted upon the washer 108 above the packing 109 around the valve stem 94.

The springs 102 and 107 resist the downward movement of the valve stem and valve member against the hydrostatic pressure which is applied to the diaphragm in the chamber 110. A screw cap 111 is provided for holding the diaphragm in position against the shoulders 112 of the casing 43. Thus pressure applied against the diaphragm in the chamber 110 will depress the diaphragm, compress the springs 102 and 107 and upon the valve 99 permitting the fluid to flow in either direction through the chambers 113 and 114 in the fitting which forms a part of the brine line 63 where this form of valve is used in the brine line. It will be understood that the mechanism of a number of these valves is similar although they are used for different purposes in the system. In this case the standard valve shown in Figure 10 has added to it the locking device of Figure 15.

Returning to Figures 1 and 6, it will be observed that a lever 115 has pivotally supported on the outer end thereof at 116 a link 117 in which is threaded a valve stem 118. This valve stem is adjustable in the link 117 and is fixed in its adjustment by the lock nut 119. This valve stem is contained within the upper portion of the brine valve casing or cap 76. This casing has threaded at 120 in the upper portion thereof an inverted cup shaped member. This cup shaped member is designated 121. Between the inner end of the

cup shaped member and a collar 122 on the valve stem 118 is a helical spring 123.

Between a shoulder 124 on this cup shaped member and the top of a packing washer 125 is a second helical spring 126 which serves to keep the packing washer 125 and the packing 127 in position. The lower end of the valve stem terminates in a needle valve member 128 which projects through the pipe 129 to close the orifice 130 leading from the pipe 75 129 into the diaphragm chamber 131 above the diaphragm 132 which controls the brine valve.

The construction of the diaphragm 132 is the same as that found in Figure 2 save that the valve member 99 is arranged as in Figure 3 above the partition 96 rather than below it. The movement of the diaphragm serves to open and close this valve.

Turning to the by-pass valve shown in Figure 4, it will be understood that the upper part of the valve is the same as that shown in Figure 2, the valve stem 94 being operated by the diaphragm 93. The valve member is slightly different in that it carries a second valve stem 151 threaded into an extension of it at 152. The valve member 99 seats on the upper side of the partition 96 as in the case of the brine valve and other valves. Below the opening 97 through which the fluid passes is located an elongated threaded collar 153.

This threaded collar carries the by-pass pipe 65 and is also provided with a restricted mouth at its lower end 154 having an opening 155 and a valve seat 156 for receiving the by-pass valve member 157. The valves designated 34 and 36 are of the type shown in Figure 2. The valve designated 38 is that shown in Figure 3 which is just as Figure 2 with the exception that the valve 99 is on the top of the partition instead of below it.

Having thus fully described my invention, what I claim as new and desire to secure by Letters Patent, is:

1. In combination, a valve consisting of a filling line, a valve member adapted to open and close said line, a valve stem, a piston on said valve stem, yielding means to move said piston and valve stem in one direction, a diaphragm connected to said valve, a chamber adapted to permit pressure to be applied to said diaphragm independent of the filling line, and a spring pressed locking member adapted to engage said piston to lock said valve in a given position, and a float and float arm connected with said locking means to retract it against a spring to unlock the valve when liquid associated with the float rises to a predetermined level.

2. In combination, a valve consisting of a filling line, a valve member adapted to open and close said line, a valve stem, a piston on said valve stem, yielding means to move said piston and valve stem in one direction, a

diaphragm connected to said valve, a chamber adapted to permit pressure to be applied to said diaphragm, and a spring pressed locking member adapted to engage said piston to lock said valve in a given position, a float and float arm connected with said locking means to retract it against a spring to unlock the valve when liquid associated with the float rises to a predetermined level, a second valve operated in one direction by yielding means and in the other direction by hydrostatic pressure working on the diaphragm, a needle valve controlling said hydrostatic pressure, a loose connection between said float arm and said needle valve, whereby the float may move a predetermined distance before the needle valve is actuated to admit the hydrostatic pressure.

In testimony whereof, I affix my signature.
CHARLES P. EISENHAUER.
